SANITARY CUSPIDOR

Filed Sept. 4, 1930

INVENTOR
BY *Samuel Tamny*
Julian Polachek ATTORNEY

UNITED STATES PATENT OFFICE

SAMUEL TAMNY, OF NEW YORK, N. Y.

SANITARY CUSPIDOR

Application filed September 4, 1930. Serial No. 479,613.

This invention relates to new and useful improvements in a sanitary cuspidor.

The invention has for an object the provision of a device of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawings and to the appended claims in which the various novel features of the invention are 15 more particularly set forth.

In the accompanying drawings forming a material part of this disclosure:

Fig. 1 is a front elevational view of a device constructed according to this invention.

Fig. 2 is a side elevational view of a device constructed according to this invention, but of a slightly modified form relative to Fig. 1.

Fig. 3 is an enlarged fragmentary sectional view of the top portions of the devices shown in Figs. 1 and 2.

Fig. 4 is a fragmentary plan view as though taken on the line 4—4 of either Fig. 1 or Fig. 2.

The sanitary cuspidor comprises a casing 10 with a top 11 having an opening 12 for supporting a cup-like vessel 13, said cup-like vessel being in the opening and having a flange 14 resting upon the marginal edge 35 of the casing top 11; a neck and base member connected with said casing for supporting it from a floor, wall or the like, a cover 15 pivotally mounted on said casing 10 for covering said cup-like vessel 13, means including a foot pedal 16 for raising said cover upon depression of the foot pedal through a predetermined distance, means for slightly raising said cup-like vessel so that it may be gripped beneath the flange for removal 45 from said casing and including a depressible peg 17 for accomplishing the raising and in the path of motion of an element 18 of said means for raising said cover, and a foot controlled means to allow further depression of 50 said foot pedal 16 for depressing said peg 17.

The casing 10 is of hollow construction and shown with tapered sides so as to be large at the top and small at the bottom. The flange 14 has its outer side curved to fit in a corresponding curve in the top member 11. 55 The top of the flange is flush with the top surface of the top member 11 so that normally the cup-like vessel 13 could not be raised out from the casing unless one's fingers were engaged inside of the vessel to draw it upwards. The neck and base member before referred to, which is connected with the casing 10 for supporting it, is shown in Fig. 1 to consist of a vertical neck member 19 connected with a base member 20 for resting upon the floor. In Fig. 2 the neck and base elements are shown to consist of a curved neck member 19' connected with a base 20 arranged in the vertical so as to be attached upon a wall or the like. 70

The pivotal mounting of the cover 15 is arranged at one point 21 along its periphery. A coaxial spring 22 is arranged upon this pivot point and acts between the cover and the casing 10 for normally urging the cover into a closed position. The means for raising said cover 15 upon depression of the foot pedal 16 consists of a radial arm 23 projecting from the cover 15 on the opposite side of the pivot point 21 and pivotally connected with said link 18 which in turn connects with one end of a lever 24 which is pivotally mounted intermediately at 25 within the neck member of the device, and which connects with a link 26 connected at its lower end with said foot pedal 16. The foot pedal 16 is pivotally mounted intermediate of its ends upon standards 27 projecting from a floor plate 28. A peg 29 projects from the pedal 16 and is engageable against the top surface of a block 30 fixed upon the floor plate 28 so as to determine the depressed position of the pedal. 80

The means for slightly raising said cup-like vessel 13 so that it may be gripped beneath the flange 14 for removal from the casing without the necessity of one's fingers engaging the inner sides comprises a ring member 31 supporting several vertical pegs 32 85 engaging in niches 33 formed in the bottom 100

of the cup-like vessel 13, and said ring being provided with an ear 34 pivotally mounted at 35 upon lugs on the inside of the casing 10. A link 36 pivotally connects with the ear 34 at one of its ends, and at its other end with one of the arms of a bell crank 37 which is pivotally mounted at 38 within the casing 10. The peg 17 is attached upon the other arm of the bell crank and projects through an opening in the casing to the exterior so as to be de-
5 pressible by the link 18.

The means to allow further depression of the foot pedal 16 for moving the link 18 sufficiently to depress the peg 17 includes a front 15 foot pedal section 16^a transversely slidably connected with a rear foot pedal section 16^b. A pin 39 projects from the pedal section 16^a and engages through a slot 40 in the pedal section 16^b for accomplishing the transverse sliding connection. A spring 41 is attached upon the section 16^b and engages the section 16^a for normally holding these sections in a fixed relative position. The block 30 is formed with two stages of heights, as may be seen in Fig. 1, so that when the foot pedal section 16^a is moved laterally the peg 29 is moved out of line from the higher height and may engage the lower height so that more downward motion is possible. The higher 25 altitude of the block 30 is indicated by reference numeral 42, and the lower altitude by numeral 43. The foot pedal section 16^a is provided with a side flange 44 which projects upwards so that one's foot may engage this 30 flange to accomplish the lateral moving of the foot pedal section.

The operation of the device may be traced by assuming it in the position as shown in Figs. 1 or 2. The foot pedal 16 may be depressed so that the peg 29 engages the surface 42 of the block 30 to cause the cover 15 to open. In this condition the vessel 13 may be used. When the foot pedal is released, the spring 21 and the weight of the various parts 45 act together to again close the cover. If it is desirable to remove the cup-like vessel 13 for cleaning purposes, the operator engages the flange 44 with the sole of his shoe and moves the foot pedal section 16^a laterally so that 50 when the foot pedal is now depressed the peg 29 is arrested by the lower surface 43 of the block 30. Such depression of the pedal causes the cover 15 to open and also moves the link 18 sufficiently so that it abuts and moves the peg 17 to pivot the bell crank 37 and transmit motion to the ear 34 for lifting the ring 31, pegs 33 and the cup-like vessel 13.

While I have shown and described the preferred embodiment of my invention, it is to be understood that I do not limit myself to the precise construction herein disclosed and the right is reserved to all changes and modifications coming within the scope of the invention as defined in the appended claims.

65 Having thus described my invention, what

I claim as new, and desire to secure by United States Letters Patent is:—

1. A sanitary cuspidor, comprising a casing with a top having an opening for supporting a cup-like vessel, a cup-like vessel in said opening and having a flange resting on the marginal edge of said casing top, a neck and base connected with said casing for supporting it, a cover pivotally mounted on said casing for covering said cup-like vessel, means including a foot pedal for raising said cover upon depression of the foot pedal through a predetermined distance, means for slightly raising said cup-like vessel so that it may be gripped beneath the flange for removal from said casing and including a de-
70 pressible peg for accomplishing the raising and in the path of motion of an element of said means for raising said cover, and foot controlled means to allow further depression of said foot pedal for depressing said peg.
75

2. A sanitary cuspidor, comprising a casing with a top having an opening for supporting a cup-like vessel, a cup-like vessel in said opening and having a flange resting on the marginal edge of said casing top, a neck and base connected with said casing for supporting it, a cover pivotally mounted on said casing for covering said cup-like vessel, means including a foot pedal for raising said cover upon depression of the foot pedal through a predetermined distance, means for slightly raising said cup-like vessel so that it may be gripped beneath the flange for removal from said casing and including a de-
80 pressible peg for accomplishing the raising and in the path of motion of an element of said means for raising said cover, and foot controlled means to allow further depression of said foot pedal for depressing said peg.

peg, said means for slightly raising said cup-like vessel comprises a ring within the casing and provided with projecting pegs engaging niches in the bottom of the vessel, 5 an ear projecting from said ring and pivotally mounted within the casing, a link connected with said ear, a bell crank connected with said link and supporting said peg, said peg extending through an opening in the 10 casing to the exterior.

4. A sanitary cuspidor, comprising a casing with a top having an opening for supporting a cup-like vessel, a cup-like vessel in said opening and having a flange resting on 15 the marginal edge of said casing top, a neck and base connected with said casing for supporting it, a cover pivotally mounted on said casing for covering said cup-like vessel, means including a foot pedal for raising said 20 cover upon depression of the foot pedal through a predetermined distance, means for slightly raising said cup-like vessel so that it may be gripped beneath the flange for removal from said casing and including a de- 25 pressible peg for accomplishing the raising and in the path of motion of an element of said means for raising said cover, and foot controlled means to allow further depression of said foot pedal for depressing said peg, 30 comprising front and rear foot pedal sections constituting said foot pedal, means for slidably connecting these sections to move trans- 35 versely, means for normally holding these sections in a relative position, a peg project- ing from the front foot pedal section and engageable with the top of a stationary block formed with surfaces at different elevations.

5. A sanitary cuspidor, comprising a casing with a top having an opening for sup- 40 porting a cup-like vessel, a cup-like vessel in said opening and having a flange resting on the marginal edge of said casing top, a neck and base connected with said casing for sup- 45 porting it, a cover pivotally mounted on said casing for covering said cup-like vessel, means including a foot pedal for raising said cover upon depression of the foot pedal through a predetermined distance, means for slightly raising said cup-like vessel so that 50 it may be gripped beneath the flange for removal from said casing and including a de- pressible peg for accomplishing the raising and in the path of motion of an element of said means for raising said cover, and foot 55 controlled means to allow further depression of said foot pedal for depressing said peg, comprising front and rear foot pedal sections constituting said foot pedal, a pin projecting from the front pedal section and engaging 60 in a slot formed in the rear pedal section for slidably connecting these sections to move transversely, means for normally holding these sections in a relative position, a peg pro- 65 jecting from the front foot pedal section and engageable with the top of a stationary block

formed with surfaces at different elevations.

6. A sanitary cuspidor, comprising a casing with a top having an opening for sup- 70 porting a cup-like vessel, a cup-like vessel in said opening and having a flange resting on the marginal edge of said casing top, a neck and base connected with said casing for supporting it, a cover pivotally mounted on said casing for covering said cup-like vessel, means including a foot pedal for raising said 75 cover upon depression of the foot pedal through a predetermined distance, means for slightly raising said cup-like vessel so that it may be gripped beneath the flange for re- 80 moval from said casing and including a de- pressible peg for accomplishing the raising and in the path of motion of an element of said means for raising said cover, and foot controlled means to allow further depression of said foot pedal for depressing said peg, 85 comprising front and rear foot pedal sec- tions constituting said foot pedal, means for slidably connecting these sections to move transversely, a spring attached upon the rear foot pedal section engages the front pedal 90 section for normally holding these sections in a relative position, a peg projecting from the front foot pedal section and engageable with the top of a stationary block formed with surfaces at different elevations. 95

In testimony whereof I have affixed my signature.

SAMUEL TAMNY.
